MATTRESS PROTECTOR

Annie Bryte Rudisill, Gastonia, N. C.

Application July 16, 1953, Serial No. 368,415

3 Claims. (Cl. 5—354)

This invention relates to new and useful improvements in mattress protectors and bed pads.

More particularly, the present invention proposes the construction of an improved mattress protector and mattress supplement which can be used on a hospital bed or any other bed in which a bed-ridden patient must remain for any length of time to protect the mattress and make the bed more comfortable for the patient.

Another object of the present invention proposes forming the mattress protector with a foam rubber pad partially covered by a rubber sheet with means on the rubber sheet to hold it in place and rubber straps removably fastened to the sheet to hold a bed sheet over the rubber pad.

Still further, the present invention proposes constructing the mattress protector with the foam rubber pad placed in the rubber sheet and the rubber sheet folded with one-inch margins over the top or upper surface of the pad, and with snap fasteners at each corner of the sheet to hold the pad in place.

As a further object, the present invention proposes a mattress protector and supplement which not only will protect a mattress but will absorb moisture quickly, will add comfort to the bed, will be soothing to tender skin and will aid allergy sufferers by holding in dust and lint.

The present invention further proposes a novel mattress protector which will hold a draw sheet firmly thereover and which can be turned over so that either side of the mattress protector can be used for the comfort of the patient.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a bed and mattress with a mattress protector and supplement constructed and arranged in accordance with the present invention thereon.

Fig. 2 is a top plan view of the mattress protector shown in Fig. 1 with parts broken away.

Fig. 3 is a sectional view taken on line 3—3 of Fig. 2.

Fig. 4 is a sectional view taken on line 4—4 of Fig. 2.

Referring more particularly to the drawings, the mattress protector and supplement has a resilient pad 15 preferably made of foam rubber. A convenient size for the pad is to have it one square yard and one inch thick. The foam rubber pad 15 may be provided with spaced recesses 16 spaced on the pad as tufts are placed on a mattress. The pad 15 has four sides 17, 18, 19 and 20, a bottom 21 and an upper or top surface 22.

2

A water repellent sheet 23 is adapted to cover the bottom of the pad 15 and its sides and peripheral portions of its upper surface. A convenient size for sheet 23 is a forty by forty inch square so that the sheet makes a one-inch overlap or fold over the top edge of the pad 15. Sheet 23 may be, and preferably is, an ordinary rubber sheet having an inner side 24 and an outer side 25.

At the corners of sheet 23 are snap fasteners 26 each having a snap fastener element 28 (see Fig. 4) and a coacting snap fastener element 28. The elements 27 are disposed on the outer side 25 of the sheet 23 and the elements 28 extend through the inner side 24 of the sheet 23 to snap onto the elements 27. In this manner, fastener means are provided removably to hold the water repellent sheet 23 on the pad 15 with substantially the entire upper surface 22 of the pad uncovered by the sheet 23.

The pad 15 so covered by the resilient sheet 23 is adapted flatly to lie on mattress 29 of bed 30. A draw sheet 31, which is an ordinary bed sheet, extends over the pad 15, the ends of the draw sheet 31 being folded over the ends of the mattress 29 and tucked under the mattress 29 between the mattress and the bed springs 32.

Spaced water repellent straps 33 and 34 in the form of rubber sheet bands of double ply and stitched, hold the bed sheet 31 in place on top of the pad 15. Snap fastener elements 35 are provided on each end of each strap 33 and 34 and coacting snap fastener elements 36 are secured to the rubber sheet 23 on the outer side of the sheet and so placed as to be disposed at opposed sides of the pad 15 when the sheet 23 is secured around the pad as above described.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A mattress protector and supplement comprising a foam rubber rectangular pad of appreciable thickness having recesses in its upper surface, a water repellent sheet covering the bottom surface, the sides and the marginal edges of the upper surface of the pad, means at the corners of the sheet for holding the sheet on the pad, a draw sheet covering the top surface of said pad, spaced straps extending across the draw sheet, and means on the straps and water repellent sheet for holding the draw sheet on the pad.

2. A mattress protector and supplement comprising a foam rubber rectangular pad of appreciable thickness having recesses in its upper surface, a water repellent sheet covering the bottom surface, the sides and the marginal edges of the upper surface of the pad, snap fastener elements on the corners of the sheet for holding said sheet on the pad, a draw sheet covering the top surface of said pad, spaced straps extending across the draw sheet, and snap fastener elements on the ends of the straps and on the water repellent sheet for holding the draw sheet on the pad.

3. In combination with bed springs and a mattress thereon, a foam rubber pad supported on the upper surface of said mattress, said pad having spaced recesses

in its upper surface, a water repellent sheet covering the bottom surface, the sides and part of the marginal edges of the upper surface of the pad snap fastener elements on the corners of said sheet, a draw sheet covering said pad, the ends of the draw sheet being tucked under the pad between the ends of the mattress and bed springs, spaced straps extending across the draw sheet, snap fastener elements on the ends of said straps, and snap fastener elements on the adjacent marginal edges of the water repellent sheet coating with the fastener elements on the straps for removably holding the draw sheet on the pad. 19
